 Textile Machine Works, Wyomissing, Pa., a
 corporation of Pennsylvania

Application August 26, 1933, Serial No. 686,922

4 Claims. (Cl. 66—172)

This invention relates to full fashioned hosiery and more particularly to single ply welt structures therefor and a method of producing the same.

5 Full fashioned hosiery, as generally defined, comprises welt, leg and foot portions either separately knit and finally joined together or knit during a continuous operation of a single machine; in either case effecting an uninterrupted 5
 10 structure of knitted fabric which, when seamed and looped together in the usual manner, will produce a stocking fashioned to conform with the shape of the member on which it is eventually to be worn.

15 The welt portion, which normally marks the beginning of a full fashioned stocking, ordinarily comprises a two-ply or double wall structure which is formed by folding the welt portion and transferring the stitches of the first knitted 15
 20 course back to the needles when the leg portion is to be started, in this way interknitting the first and last courses of the welt and consequently preventing the raveling of the fabric which would normally occur were the loops of 25
 25 the first course permitted to remain as the selvedge edge of welt.

30 When knitting a stocking the first course, ordinarily a loose course, is laid across the noses of the sinkers and dividers and forced thereby between the needles; the machine is then turned until the needles have moved downward sufficiently to catch the thread under their respective beards and the sinkers and dividers have been drawn back until the loops are about ready 30
 35 to fall from their noses. At this juncture the welt bars are operatively positioned, the welt hooks being inserted sufficiently deep between the needles to be positioned between the lower edge of the sinkers and dividers and the upper surface of the knockover bits. A further movement of the machine causes the loops to clear the sinkers and dividers, while a forward upward movement of the welt bar brings the welt hooks into hooking engagement with the sinker 40
 40 and divider loops. The welt bar is then connected to the draw-off motion and the fabrication 45
 45 of the welt continued.

45 After a sufficient length of fabric has been 50
 50 knitted to form the welt, the machine is stopped, with the needles up and the sinkers and dividers retracted, and the usual welt turning operation effected during which the sinker and divider loops, now held by the welt hooks, are topped therefrom onto the needles to produce a folded 55
 55 or two-ply welt. The welt bars are then re-

moved and wire rods placed in the folded hem or welt portion through which connection is made with the draw-off motion. During the knitting of the succeeding course single loops are interlaced with the double stitches, now maintained by each needle as a result of the welt turning operation, after which the fabrication of the leg portion is continued in the usual manner.

5 The turning of the welt as above described is 10 an essential operation necessarily associated with the production of two-ply welt full fashioned hosiery inasmuch as no method has heretofore been introduced by which selvedge courses could be produced whose structure would be ravel-proof. Thus although the double wall structure 15 of the welt is not always desirable, its employment has heretofore been necessitated partly because of the tendency towards raveling which is characteristic of free ends of knitted fabric.

10 In accordance with the present invention I 20 provide a selvedge for a single ply welt forming the upper end of full fashioned hosiery which in addition to being ravel-proof will likewise possess the proper degree of elasticity proportional to the remainder of the knitted fabric. I pref- 25
 25 erably use an elastic yarn such, for instance, as "Lastex", or any other suitable stretchable yarn, to form the first row of loops of the welt and I interloop the loops of said first course with the 30
 30 needle loops of the second course. I have found the "Lastex" yarn quite unbreakable under conditions encountered by stockings. The elastic yarn, due to its elastic properties, when subsequently substantially straightened definitely arranges the loops of the selvedge in a manner to 35
 35 prevent any raveling thereof due to the first row of loops resolving itself into a crosswise extending tie member which passes through the loops intermediate the needle loops of the second course in such a manner to make raveling of 40
 40 the fabric impossible. Furthermore, due to the elasticity of this thread, the upper edge of the welt portion is provided with the proper amount of stretchability to permit the stocking to be readily drawn on and from the member upon 45
 45 which it is to be worn, and likewise effects a snug fit thereon. This elastic feature also results in a slight degree of garter action which aids in keeping the stocking in the correct longitudinal and circumferential position on the leg member upon which it is worn, in addition to preventing curling of the free end thereof.

50 Accordingly, one object of my invention is to provide a novel single-ply welt structure for full 55

fashioned hosiery, in which the first course of loops forming the upper or free edge thereof has a ravel-preventing thread passing therethrough whereby the entire welt structure is 5 made ravel-proof.

Another object of my invention is to provide an elastic ravel-proof edge structure to promote the correct fit of the top of the stocking as well as to substantially ensure against rupture of such 10 structure.

With these and other objects in view, which will become apparent from the following detailed description of the illustrative embodiment of the invention shown in the accompanying drawings, 15 my invention resides in the novel fabrics, and articles, and method of producing the same, as hereinafter more particularly pointed out in the claims.

In the accompanying drawings:

20 Fig. 1 is a side elevation of a conventional full fashioned stocking including the present novel welt selvedge construction;

25 Fig. 2 is a magnified plan view showing the loop formation of my novel welt structure;

25 Fig. 3 is a progression of Fig. 2 showing the end thread drawn taut;

Fig. 4 is a sectional view taken on line 4—4, Fig. 1;

30 Figs. 5, 6 and 7 are progression diagrammatic views illustrating the mechanism and manner in which my novel welt structure is produced.

Preparatory to the fabrication of my single-ply welt the knitting machine is turned to the customary starting position in which the needles 35 11, rigidly maintained in spaced relationship in the needle bar 12 by means of the clamps 13, are elevated as shown in Fig. 5, the sinkers 14 and dividers 15, meanwhile, being in their retracted position, and the knockover bits 16 maintaining the relative position shown. With the various members thus positioned the elastic yarn 17 is laid across the noses of the sinkers 14 and dividers 15 and successively sunk thereby between the spaced needles 11 to form the: sinker (S), 40 needle (N), and divider (D) loops respectively, substantially as shown in Fig. 5. The procedure thus far detailed corresponds with the usual well known method of producing the normal knitted course. Now, however, in order to effect a ravel-proof edge for a single-ply welt (A), I provide 45 the knitting machine with needle engaging points 18 which are aligned with alternate needles and maintained in spaced relationship in the point bar 19 by means of the clamping action exerted by clamp 21 in the manner shown in Fig. 5. The rod 22, which supports the point bar 19 by means of the intermediate bracket 23, is in turn slidably and rotatively mounted in the bearing 24 which in turn is supported by the 50 front narrowing shaft 25. The front narrowing shaft 25 is rigidly held in brackets 26 and maintained in parallel alignment with the back narrowing shaft 27 by means of the guide arms 28 in the manner shown in Fig. 5. Upward and 55 downward motion is imparted to the front narrowing shaft 25, and consequently to the points 18, by means of cam controlled levers (not shown) joined to the front narrowing shaft 25.

As will be observed in the accompanying drawings, the point members 18 are formed to coact with the beards 11a of selected needles 11 for the purpose of closing the beards before the loops are positioned therebeneath, and in this way causing the loops (N) on selected point aligned needles 70 to slide over the outside of the beards 11a instead

of thereunder as is normally done. Thus, with the various parts positioned as in Fig. 5, and the sinker (S), needle (N) and divider (D) loops arranged as shown, the machine is further advanced through its cycle causing the needles 5 11 to descend while the sinkers 14 and dividers 15 are gradually retracted. Meanwhile the point bars 19 are prevented from further descent by means of auxiliary equipment, such for instance as shown and described in my co-pending application, Serial No. 606,795, filed April 22, 1932. 10

After the beards 11a of the needles 11 have entered between the knockover bits 16 the machine is stopped and the welt bars 29 inserted in the usual manner. The machine is again 15 turned until the sinkers 14 and dividers 15 are in their inoperative retracted positions and the needles 11 have descended below the upper surface of the knockover bits 16, while adjacent sinker and divider loops, indicated at S and D in 20 Fig. 5, are caught by the welt hooks 31 as shown in Fig. 6. The welt hooks 31 are then, in turn, attached to the draw-off motion (not shown) and the fabrication of the welt (A) is continued 25 in the usual manner.

It will here be observed that the loops (N) of the point aligned needles have been cast therefrom whereas the intermediate needles retain their respective loops in the usual manner. Thus, adjacent welt hooks, instead of individually 30 retaining separate sinker (S) and divider (D) loops, now combinedly maintain a single loop (E) composed of a released needle loop (N) in addition to the adjacent sinker and divider loops, substantially as illustrated in Figs. 6 and 7. 35

During the return of the needles 11 to their starting position, the points 18 are likewise raised to the relative position shown and then inoperatively positioned by means of a forward upward rotative movement of the rod 22. The 40 points 18 are thus maintained in their inoperative positions until the fabrication of the leg blank of the stocking, Fig. 1, has been completed, after which the point bar 19 is again lowered 45 into their point operating position preparatory to the fabrication of another welt (A).

With the points 18 inoperatively positioned the second course is produced in the usual well known manner; consequently, during the looping operation of the latter the uninterrupted 50 series of needle loops are interknit with the loops of the previous course to effect the structure shown in Figs. 2 and 7. As there shown, the loops intermediate the needle loops of the second course are interlooped with the needle loops of 55 the previous course, (see Fig. 6,) in the manner necessary to effect the desired ravel-proof edge by which my single-ply welt construction for full fashioned hosiery is distinguished.

Likewise, following the completion of the 60 ravel-proof course, the elastic-thread carrier may readily be replaced by a carrier containing yarn of the desired qualities for completing the welt, or the knitting with the elastic yarn may be continued if an all-elastic welt is desired. 65 The yarn used to form the body of my novel welt (A) preferably embodies such properties that the resulting welt portion will possess qualities comparable with those ordinarily associated with the usual two-fold welt.

The knitted welt fabric first appears as shown in Fig. 2; and when the elastic yarn 17 has straightened, the completed fabric will appear as shown in Fig. 3.

Furthermore, I accomplish said desired struc- 70 75

ture while effecting an appreciable saving in both time and material, due to the fact that the welt turning operation is eliminated while a fifty per cent saving in yarn is effected by making the welt of single-ply construction, as in Fig. 4, instead of the usual double wall type. In order to effect my novel single-ply welt possessing the desired degree of strength, elasticity and wear-resisting properties while, however eliminating the undesired bulkiness ordinarily associated with the usual two-fold or double-ply structure, I use a heavier and more durable yarn than is normally employed to knit the folded welt; the yarn of welt A, likewise is substantially heavier than that used to fabricate the main body portions of the leg B and foot C; the relative thickness of said welt A and the leg portion B is more or less diagrammatically illustrated in Fig. 4. Thus the welt A consequently possesses sufficient strength to resist the wear created by the engaging and disengaging of the usual garter clasps as well as the strains transmitted thereto, as, for example, occasioned by the bending of the knee.

The arrangement of the loops in my ravel-proof course, relative to the loops of the remainder of the welt portion, is illustrated in the enlarged view of Fig. 2. If the yarn 17 is of the usual non-elastic type it will retain the scalloped effect (see Fig. 2) when the welt is unstretched and will be drawn taut as in Fig. 3, only when coursewise tension is applied. However, if elastic yarn is used to form the initial course the yarn 17 will normally contract to produce the transverse tie member, as in Fig. 3, coursewise stretching likewise being permitted in this case because of the elastic properties of the yarn 17. In accordance with Fig. 3, the yarn 17 is interlaced with the loops of the adjacent course in such a manner as to effect the desired ravel-proof selvedge.

Thus in conjunction with effecting an appreciable saving of time by eliminating the usual

welt turning operation in addition to saving fifty per cent of material without sacrificing any degree of strength, elasticity or durability, as compared with the usual two-fold welt construction, I further provide a means whereby a ravel-proof edge may be incorporated as the first course of knitted loops and consequently permit the adoption of a single-ply knitted fabric as the welt portion of full fashioned hosiery.

Of course, the improvements specifically shown and described, by which I obtain the above results, can be changed and modified in various ways without departing from the invention herein disclosed and hereinafter claimed.

I claim:

1. A stocking comprising a ravel-proof top edge consisting of a marginal body yarn course and an elastic yarn separate from the body yarn extending substantially parallel to said top edge through all of the loops of said course.

2. A full-fashioned stocking comprising a ravel-proof top edge consisting of a marginal body yarn course and a rubber-cored yarn separate from the body yarn extending substantially parallel to said top edge through all of the loops of said course and joined at its ends adjacent to the back seam of the stocking.

3. A full fashioned stocking including a ravel-proof knitted top edge consisting of a marginal yarn course and a rubber cored yarn separate from the yarn of said marginal course extending substantially parallel to said top edge through all the loops of said course and threading through adjacent loops thereof from opposite directions and joined at its ends adjacent the back seam of the stocking.

4. A stocking having a single ply welt comprising a ravel proof top edge consisting of a marginal body yarn course and an elastic yarn separate from the body yarn of said welt and extending substantially parallel to said edge through all the loops of said course.

GUSTAV GASTRICH.
